JOHN G. CAYTEN, OF LOWELL, MASSACHUSETTS.

SHUTTLE BINDER AND CHECK FOR LOOMS.

1,120,026.

Specification of Letters Patent.

Patented Dec. 8, 1914.

Application filed April 4, 1914. Serial No. 829,448.

To all whom it may concern:

Be it known that I, JOHN G. CAYTEN, a citizen of the United States, residing at Lowell, in the county of Middlesex and 5 Commonwealth of Massachusetts, have invented a certain new and useful Improvement in Shuttle Binders and Checks for Looms, of which the following is a specification.

10 This invention relates to shuttle binders and checks for looms.

The object of this invention is to allow a comparatively easy entrance of the shuttle into the shuttle-box by making the initial 15 pressure of the binder very light and when the shuttle has gone more than half way into the box, by increasing the binding pressure so that when the shuttle has reached the end of its path the pressure of the check 20 and binder on the shuttle is such as to prevent any rebound of the shuttle in the box, so that the shuttle is absolutely locked until the next stroke of the picker. The check and binder coöperate so that the outward 25 movement of either increases the pressure of the other.

This invention allows me to dispense with the usual binder springs,—(commonly leaf-springs bolted to the lay-beam and pressing 30 against the outer side of the binder)—which wear rapidly, and with the dagger-rod spring—(a coiled wire spring surrounding the dagger-rod near the middle of the same and at its opposite ends connected to said 35 rod and to the lay beam to hold the dagger-rod fingers against the binders) which frequently breaks; and thus effects a considerable saving. The dagger-rod spring has the disadvantage of tending to expand longitudinally and thereby pushing the dagger-rod 40 endwise in such a manner as to crowd one dagger-rod finger toward the hub of the corresponding binder and of drawing the other dagger-rod finger nearer the free end 45 of the other binder causing the fingers to press unequally the corresponding binders and sometimes one of these fingers is drawn off from the free end of its binder causing 50 breaking of the warp, the shuttle and other parts. The advantage of a loose box is in enabling the binder stud to remain in one position and the screws which hold the top and back of the shuttle-box to be fixed without the need of adjustment when changes of 55 weather from day to day cause a swelling or

shrinking of the shuttle because the check can be adjusted much more easily by moving the check in toward the box to cause the check to project farther into the box when the shuttle shrinks and in the opposite direction 60 when said shuttle swells, or the same result may be attained by stretching or relaxing the check-spring.

In the accompanying drawing, Figure 1 is a plan of the left end portion of a lay-beam 65 and of its shuttle-box with my improvement applied thereto; Fig. 2, a rear elevation of the same; Fig. 3, a left end elevation of a part of the loom-frame, shuttle-box, shuttle, binder, check, dagger-rod, dagger and frog, 70 and a section of the lay-beam on the line 3 3 in Fig. 1; Fig. 4, a plan of the check detached; Fig. 5, a side elevation of the arm of the check engaging a part of the check-spring; Fig. 6, a rear elevation of the 75 binder; Fig. 7, a plan of a slight modification, showing the check pivoted on the binder instead of on a separate stand, showing also the check-spring, and a part of the check lever and shuttle; Fig. 8, a rear elevation of the pivoted end portions of the 80 modified binder and check shown in Fig. 8.

A indicates the lay-beam, which serves also as the shuttle-race and bottom of the shuttle-box and is provided with the slot a, 85 in which the picker-stick B swings to throw the shuttle C; D denotes the binder provided with a hub d which turns on a vertical binder stud d¹; E represents the dagger-rod or protector-rod which turns in journals 90 (one of which is shown as e, Fig. 3) secured to the underside of the lay-beam, and has a dagger e¹ which is normally raised to clear the frog F by a shuttle in either box pressing the corresponding binder against a dagger-rod finger e², but when a shuttle is in 95 neither box the dagger is down in the position shown by dotted lines in Fig. 3 and in the forward movement of the lay will strike said frog and move the same to throw the 100 shipper lever out of its holding notch and stop the loom, all the above named parts being of the usual construction and operation except as hereinafter described.

The binder D is provided with an opening d² from front to back to admit the swell g of the check G which is pivoted at its outer end on a vertical stud g¹, supported on a stand g² bolted to the back of the lay-beam A and by means of the slot g³ adjustable to 110

bring the swell to work freely in the opening d^2 without striking the ends of said opening.

The stud g^1 is provided with a shoulder 5 g^4 which rests on the top of the horizontal upper part g^5 of the stand g^2 and the reduced part of said stud below said shoulder is passed down through a slot g^6 in said stand and threaded to engage a nut g^7 which, being loosened, allows said stud g^1 to be adjusted toward and from the shuttle-box to cause a greater or less projection of the swell g into the box as the shuttle becomes worn or when a worn shuttle is replaced by 10 a new or laterally thicker one. The inner end of the check is provided with an arm g^8 which extends horizontally backward and is transversely concaved at g^{10} to fit a spiral spring H one end of which is a hook h which engages one of a series of holes g^9 in the check and the other end of which engages the short arm i of a horizontal check-lever I which turns upon a vertical pivot stand i^1 and has another arm i^2 which bears against 15 the back of the adjacent dagger-rod finger e^2 and presses said finger against the corresponding binder, said arm i^2 being hollowed at i^3 , as shown in Fig. 1, to receive said finger. By changing the hook h of the spring H from one to another of the holes g^9 nearer to or farther from the check-lever the tension of said spring H may be diminished 20 or increased.

The check devices herein described will be 25 applied to each end of the lay-beam and may be used equally well where the binder is at the front of the shuttle-box as where it is in the position shown in the drawing.

When the shuttle enters the box it is first 30 pressed very slightly by the binder, then strikes the check and crowds said check outward stretching the spring and crowding the dagger-rod finger with force against the binder and pressing the latter against the 35 shuttle. The outward movement of either the binder or check increases the tension of the spring and causes the other of these parts to press with greater force upon the shuttle. By careful adjustment of the parts

the shuttle may be stopped against the 50 picker when the picker-stick is at the outer end of its slot, without inflicting a violent blow upon the picker and thereby incurring the risk of breaking said picker stick.

In the modification shown in Figs. 7 and 55 8 the check G^1 is represented as pivoted at g^{11} between ears d^3 d^4 integral with the binder D^1 , thus dispensing with the separate stand g^2 shown in Figs. 1-3, the body 60 of the check extending from the middle of its bearing sleeve g^{12} instead of from the top of the corresponding sleeve g^{13} in Fig. 2. The other parts shown in these Figs. 7 and 8 are shown in the figures previously described and operate as above described. 65

I claim as my invention:

1. The combination in a loom, of a binder having an opening, a pivoted check extending through said opening into the shuttle-box and into the path of the shuttle, the 70 dagger-rod having a finger, and connecting means between said check and said finger to press said finger against said binder.

2. The combination in a loom, of a binder having an opening, a pivoted check extending through said opening, a check-lever, a spring connecting said check and one arm of said check-lever, the dagger-rod having a 75 finger, the other arm of said check-lever pressing said finger against said binder. 80

3. The combination in a loom, of a binder having an opening, a pivoted check extending through said opening, a check-lever, a spring connecting said check and one arm of said check-lever, the dagger-rod having a 85 finger, the other arm of said check-lever pressing said finger against said binder, said check having an arm arranged in contact with said spring to increase the tension of said spring and the pressure of said finger 90 on said binder as the check is forced out of the box by the incoming shuttle.

In witness whereof, I have affixed my signature in presence of two witnesses.

JOHN G. CAYTEN.
